DESIGN FOR A DOLL OR SIMILAR ARTICLE

Howard Bay, New York, N. Y., assignor to The Petroleum Industry Exhibition Inc., New York, N. Y., a corporation of Delaware

Application January 31, 1939, Serial No. 82,689

Term of patent 3½ years

To all whom it may concern:

Be it known that I, Howard Bay, a citizen of the United States, residing at 35 West 52nd Street, in the city, county, and State of New York, have invented a new, original, and ornamental Design for a Doll or Similar Article, of which the following is a specification, reference being had to the accompanying drawing, forming part thereof, in which:

Fig. 1 is a side perspective view of a doll showing my design, the eyes being in partly closed position and

Fig. 2 is a front perspective view thereof with the eyes in open position.

I claim:

The ornamental design for a doll or similar article, as shown.

HOWARD BAY.
